J. P. MALONE

VACUUM CLEANING APPARATUS

Filed Jan. 25, 1922

Fig. 1.

James P. Malone,
Byrne, Gibbons, Bryan, Purnell &
Co., Atty.

UNITED STATES PATENT OFFICE.

JAMES P. MALONE, OF PITTSBURGH, PENNSYLVANIA.

VACUUM-CLEANING APPARATUS.

Application filed January 25, 1922. Serial No. 531,610.

To all whom it may concern

Be it known that I, JAMES P. MALONE, a citizen of the United States, residing at Pittsburgh, Allegheny County, Pennsylvania, have invented a new and useful Improvement in Vacuum-Cleaning Apparatus, of which the following is a full, clear, and exact description, reference being had to the accompanying drawings, forming part of this specification, in which—

Figure 1 is a vertical sectional view through a cleaning apparatus constructed in accordance with the present invention;

Figure 2 is a sectional view through a part of the apparatus illustrated in Figure 1 showing the separating hood in deflated condition, and

Figure 3 is a detail sectional view on an enlarged scale.

The present invention relates broadly to cleaning apparatus, and more particularly to vacuum cleaning apparatus having a combined dry and wet separating tank.

It has heretofore been attempted to clean rugs, carpets and the like by the use of a cleaning fluid and a vacuum cleaning apparatus for removing the fluid. Not only has considerable difficulty been experienced in making a suitable apparatus for taking care of the dirt and water, but the water has attacked the glue sizing and caused the nap to pack down. This is very objectionable, and has prevented the extensive use of such methods. By the present invention, however, these objections are entirely overcome, as I have invented an apparatus for handling the dirt and water extracted.

It will be understood that the accompanying drawings constituting part of this specification are for purposes of illustration only, and that changes may be made in the details of construction and the operation of the parts without departing from the spirit of the invention or the scope of my broader claims.

In the drawings, there is illustrated a vacuum cleaning apparatus comprising a base 2 carried by castors 3 enabling it to be easily moved from place to place as required. Extending upwardly from the base 2 are a series of vertical supports 4 secured at their upper ends in any desired manner to a ring 5. Detachably supported within the ring 5, and resting therein entirely by gravity, is a combined dry and wet separator tank 6. This tank is preferably constructed with its

walls converging downwardly to a central outlet which may be closed by a removable closure 7 of any desired construction to permit cleaning of the tank. Adjacent the closure 7 may be provided a drain 8 providing a supplemental outlet therefor which may be used at predetermined intervals.

Extending tangentially into the tank 6 intermediate the ends thereof, but preferably adjacent the upper portion is an inlet 9. By reason of the tangential disposition of this inlet it will be apparent that the entering stream is given a whirling motion within the separating tank 6, thereby causing the solid particles to cling to the converging walls, but permitting the air and lighter particles to separate therefrom and pass upwardly from the tank. The outlet from the tank comprises a substantially centrally positioned opening 10 formed in a baffle plate 11 preferably having all of its walls tapered downwardly. Located above the opening 10 is a second baffle 12 having downwardly sloping sides. This baffle is adapted to deflect into the tank 6 any heavier particles carried therefrom by the rising air currents.

Supported above the tank 6 is a casing 13 having an outlet 14 connected in any desired manner, as by a flexible hose 15 with a disinfecting tank 16. This disinfecting tank is also preferably mounted in such manner that it can be easily moved from place to place, and is formed with a submerged jet 17 adapted to discharge below a screen 18 whereby air bubbles are effectively broken up during their travel through the disinfecting and filtering fluid 19. The outlet 20 from the tank 16 may lead in any desired manner to a motor or other mechanism for producing the desired air currents through the apparatus.

Positioned within the casing 13 is a flexible hood 21, formed of any desired material, and having its lower edge detachably secured in position about an upstanding flange 22 by a clamping band 23. At its upper end the hood 21 has secured thereto any desired means, such as a bag of shot 24 for causing the same to normally tend to drop into the position illustrated in Figure 2. This movement, when the hood is deflated, is limited by a restraining member 25 which imparts a jar to the hood causing the particles of dirt to become dislodged therefrom and fall downwardly on to the baffles 11 and 12 and

thence through the outlet 10 into the tank 6. When the vacuum is again established the hood will be inflated, causing the weighted upper end to move upwardly. Movement 5 in this direction will be limited by a stop plate 26, forming a baffle, and supported in any desired manner so as to form a tortuous path for the air attempting to pass from the casing 13 to the outlet 14 through the opening 27. When the hood engages the plate 26 it will have imparted thereto another jar which assists in the cleaning of the hood.

If desired, the casing 13 may be formed with straps 28 adapted to cooperate with 15 staples 29 by means of which the parts of the apparatus may be locked in position.

In operation, when the cleaning nozzle which is secured in any desired manner to the inlet 9 is placed in engagement with 20 the rug or carpet being cleaned, the air flow through the hood 21 will be slightly restricted and this will result in a deflation of the hood. Each time the nozzle is lifted the hood will be fully inflated. It will be 25 apparent, therefore, that I have provided means for automatically cleaning the flexible hood during the operation of the apparatus. If desired, the hood may be cleaned by manually cutting off the flow of air there- 30 through in any desired manner.

In cleaning, I first preferably subject the rug or carpet to the action of the apparatus in the usual way to remove all loose dirt therefrom. I then apply, preferably, by 35 means of a large scrubbing brush of suitable construction, a limited amount of a cleansing fluid to a limited area of the rug or carpet, and scrub the same vigorously to loosen all grease and dirt which has become 40 packed into the nap thereof. Immediately after this operation, and before the cleansing fluid has had an opportunity to attack the glue sizing, I withdraw all of this fluid together with the foreign material loosened 45 thereby by subjecting said area to the action of the vacuum cleaning nozzle. This operation is then repeated until the entire 50 surface has been cleaned. I have found this method to be most effective when operating on successive strips, each having a width substantially equal to the length of the brush by which the cleansing fluid is applied and to the length of the nozzle by which the 55 suction is applied. For example, successive strips of approximately 12" may be easily and quickly cleaned and the cleansing fluid removed before it has had an opportunity to soften the glue sizing.

By reason of the fact that the inlet 9 is 60 tangentially arranged, water is prevented from passing upwardly into the hood 21, and I have found that the arrangement of baffles cooperates with the separating tank in such manner that either when using it 65 as a dry separator or a wet separator a cen-

tral column of dry rising air is formed. I have found it to be highly essential in an apparatus of this character to provide some means for preventing the dirt from becoming caked on the hood 21, as will be the 70 case with such a construction as illustrated in the German Patent No. 272384 if it were attempted to use such a construction with a cleansing fluid. Furthermore, it is necessary to provide some means for limiting the 75 extending movement of the hood during inflation as otherwise it rapidly becomes torn or broken.

The advantages of the present invention 80 arise from the provision of an apparatus by means of which both a dry and a wet cleaning operation may be effectively produced for insuring the removal of all foreign material from a rug, carpet, or the like.

I claim:

1. In a vacuum cleaning apparatus, a separating tank having a tangential inlet whereby entering air is given a whirling motion and a centrally located restricted outlet for said air, a baffle cooperating with 90 said outlet, a flexible hood receiving the air from said outlet, means for causing said hood to deflate and inflate, and means independent of the hood structure for limiting movement of the free end thereof upon deflation and inflation and thereby imparting a cleaning jar to said hood both during 95 deflation and inflation.

2. In a vacuum cleaning apparatus, a separating tank having downwardly sloping converging walls and a tangentially extending inlet, a downwardly sloping deflector cooperating with the upper end of 100 said tank and provided with a centrally located restricted outlet, a baffle for said outlet, a hood for receiving the flow through said outlet, and means independent of the hood structure for limiting movement of the free end thereof upon deflation and inflation and thereby imparting a cleaning jar to said hood both during deflation and inflation, 110 substantially as described.

3. In a vacuum cleaning apparatus, a separating tank having downwardly sloping converging walls and a tangentially extending inlet, a downwardly sloping deflector cooperating with the upper end of 115 said tank and provided with a centrally located restricted outlet, a baffle for said outlet, a flexible hood cooperating with said outlet, said hood having a weighted upper end, means cooperating with said weighted upper end for limiting the upward movement of said hood during inflation, and a 120 restraining member secured to said hood for limiting the downward movement thereof during deflation, both of said means being adapted to impart jars to said hood for cleaning the same, substantially as described,

4. In a vacuum cleaning apparatus, a separating tank, means for producing a vacuum therein, means for delivering dirt laden air thereto, a flexible hood intermediate said means adapted to be deflated and inflated, and means independent of the hood structure for limiting movement of the free end thereof upon deflation and inflation and thereby imparting a cleaning jar 15 to said hood both during deflation and inflation.

5. In a vacuum cleaning apparatus, a separating tank, means for producing a

vacuum therein, means for delivering dirt laden air thereto, a flexible hood intermediate said means adapted to be deflated and inflated, and means for automatically imparting a jar thereto both upon inflation and deflation movements thereof, said hood having a weighted upper end for increasing the jar imparted thereto, substantially 20 as described.

In testimony whereof I have hereunto set my hand.

JAMES P. MALONE.
